IRA A. McCORMACK, OF NEW YORK, N. Y.

SEAL FOR LOCKS.

1,352,073.

Specification of Letters Patent. Patented Sept. 7, 1920.

Application filed March 1, 1919. Serial No. 280,071.

To all whom it may concern:

Be it known that I, IRA A. McCORMACK, a citizen of the United States, and a resident of New York, in the county of New York and State of New York, have invented a certain new and useful Improvement in Seals for Locks, of which the following is a full, clear, and exact specification.

This invention relates to a class of devices adapted to be used in conjunction with locks.

My invention has for its object primarily to provide a device or seal adapted to be employed on locks, especially of types known as padlocks which are commonly made with a casing having a shackle operable by a key, whereby the breaking of the seal will be required, in order to permit insertion of the key in the hole of the casing of the lock, and which is of a form to allow a record to be kept of the official breaking of the seal prior to subsequent opening of the lock so that in event of surreptitious breakage of the seal the act may be readily detected. This is accomplished mainly by the provision of a fragile plate having a body or surface portion, and the plate is adapted to be removably mounted on the casing of the lock so as to cover the key hole of the casing, while on the surface portion may be provided a record of the container as well as allowing a record to be kept of the official breakage of the seal and opening of the lock. Retaining means are also provided whereby the movement of the shackle of the lock when closed on the casing will cause the plate to be engaged in a manner so that its breakage will be required to obtain access to the key hole.

A further object of the invention is to provide a seal of a simple and efficient construction which is adapted to be made of any suitable material in any desired shape and size.

With these and other objects in view the invention will be hereinafter more particularly described with reference to the accompanying drawing forming a part of this specification in which similar characters of reference indicate corresponding parts in all the views, and will then be pointed out in the claim at the end of the description.

In the drawing, Figure 1 is an elevation of one form of lock having parts of the retaining means for removably holding my improved seal thereon, the shackle of the lock being in an open position.

Fig. 2 is an elevation of the lock with the seal applied thereon, and which shows the shackle in a closed position.

Fig. 3 is a perspective view of the seal proper.

Fig. 4 is a fragmentary detail sectional view taken on the line 4-4 of Fig. 2.

Fig. 5 is a front elevation of another form of lock with a slightly modified type of the seal applied thereon, the shackle of the lock being shown in an open position.

Fig. 6 is a similar view showing the shackle of the lock in a partly closed position.

Fig. 7 is a sectional view taken on the line 7-7 of Fig. 3, and

Fig. 8 is an elevation of a record card adapted to be carried by the seal.

The device or seal has a fragile element or plate 10 made of porcelain, metal or other suitable material whereby it may be severed or broken with comparative ease by the use of a suitable implement, and this plate may be of any desired shape and size so as to be applied on the casing, as 11, of a lock, preferably of a form commonly known as a padlock, as 12, having a shackle or bolt, as 13, which is self-locking when closed on the casing. In the casing the usual hole, as 14, for insertion of a key to unlock the shackle, and the fragile plate 10 has a body or surface portion 16 to allow of a suitable record, as 17, to be inscribed or otherwise provided thereon whereby a record may be kept of the number of the seal as well as the number of the container, date of applying the seal on the lock, and the name of the agent or person who fixed the seal on the lock. In the face of the surface portion 16 of the fragile plate opposite to the indicia 17 may be a recess, as 18, for removably holding a card or the like, as 19, on which may be inscribed a record of the opening of the breaking of the seal and opening of the lock by the authorized official or person.

The surface portion 16 of the plate 10 may be of a shape and size to extend from the end of the shackle 13 which is pivoted to the casing of the lock to a part of the casing so that the plate 10 will cover the key hole 14 of the casing. Retaining means of any suitable type may be employed for removably holding the fragile plate on the casing of the lock over the key hole, though I prefer to accomplish this purpose in a manner best adapted for the type of lock

to which the fragile plate is applied. For example, when the seal is designed for use on the form of lock shown in Figs. 1 and 2, the retaining means consists of providing on 5 the pivot 20 of the shackle a head, as 21, which protrudes beyond the wall of the casing 11 of the lock having the key hole 14. The head 21 of the pivot 20 is preferably substantially rectangular in shape, and this 10 head is provided on the pivot so that its underside is spaced from the casing. Protruding from the casing 11 of the lock and in spaced proximity to the key hole 14 is a fixed pin 22 having on its free end a head 15 23 which is also spaced from the casing. Integrally formed on one part of the fragile plate 10 is an extension member 24 having an aperture 25 therethrough, and this aperture is substantially rectangular in shape as 20 well as being of a size to freely accommodate the head 21 of the pivot 20 of the shackle of the lock. Also integral with a part of the plate opposite to the apertured extension member 24 is a protruding notched 25 member 26 which is of a size to freely accommodate the part of the pin 22 of the casing of the lock under the head 23 of the pin. The surface portion 16 of the plate 10, apertured extension member 24 and the 30 notched member 26 are of combined sizes as well as being relatively arranged so that when the plate is disposed on the casing 11 of the lock to cover the key hole 14 the plate may be guided whereby the pin 22 will 35 be disposed in the notch of this member and so that the rectangular head 21 of the pivot 20 of the shackle of the lock will protrude through the aperture 25 of the extension member 24 of the fragile plate. The pivot 40 20 of the shackle of the lock and the aperture 25 of the extension member 24 are so relatively located that when the shackle is swung open from the casing of the lock the head 21 of the pivot 20 will be positioned to 45 allow the head to pass through the aperture 25 of the extension member 24 when the plate is disposed on the casing, as above explained, and when the shackle is swung to a closed position on the casing the pivot 20 50 will be rotated sufficiently to position its rectangular head 21 crosswise of the rectangular aperture 25 of the extension member 24 of the fragile plate 10. The seal will then be held on the lock against accidental 55 displacement as well as being held so that breakage or severance of the plate will be required, in order to allow access to the key hole of the lock to be obtained.

The seal may also be designed for use in 60 conjunction with the form of lock shown in Figs. 5 and 6, in which instance the shackle or bolt 13 is movable to locked and unlocked positions by being swung crosswise of a notch, as 26^a, provided in the part

of the casing 11 opposite to the key hole 65 14. Protruding from the part of the shackle which is movable in the notch 26^a is a pin 27 extending out of the notch for some distance beyond the wall of the casing having the key hole, and this pin 27 terminates with 70 a head 28. Also projecting from the wall of the casing in proximity to the key hole 14 is a second pin 29 having a head 30 which is spaced from the casing. The pins 27 and 29 provide the retaining means for releasably locking the fragile plate 10 to this form of lock, and adapted to coact with these pins, on one part of the surface portion 16 of the plate is integrally formed an extension member 31 which is somewhat of a U 75 shape to provide a notch, as 32, having an angularly curved terminal portion, as 33. The notch 32 is adapted to receive the part of the pin 27 under its head 28, and the curved portion 33 of the notch is arranged 80 to allow the pin to move thereinto when the shackle is closed to a locking position on the casing of the lock, the head 28 of the pin 27 being, larger, as shown, than the width of the notch 32. Integrally formed 85 on the part of the surface portion 16 of the plate 10 which is opposite to the U-shaped extension member 31 is another substantially U-shaped extension member, as 34, to provide a notch, as 35, for reception of the part 90 of the pin 29 under its head 30. This form of the plate 10 is applied to the lock by the shackle 13 being swung to an open position at which time the pin 27 will also be guided outwardly of the notch 26 of the casing 11 of 95 the lock. The plate 10 is then arranged on the lock so that the pin 29 is seated in the notch 35 of the extension member 34 of the plate and so that the notch 32 of the extension member 31 of the plate is in register 100 with the notch 26 of the casing of the lock. When the shackle 13 is moved to a locked position in the casing the pin 29 will pass first into the notch 32 of the extension member 31 and afterward into the curved part 33 105 of this notch. The plate 10 with its extension members 31 and 34 will thereby be removably held on the lock so that breakage of the plate will be required before a key is inserted in the hole of the casing for unlocking the lock. Prior to applying the plate 10 to the lock in the recess 18 of the plate may be placed the card 19 on which 110 may be designated the date and place when the lock was opened as well as the name of 115 the person operating the lock.

In the foregoing description, I have embodied the preferred form of my invention, but I do not wish to be understood as limiting myself thereto as I am aware that modifications may be made therein without departing from the principle or sacrificing any 120 of the advantages of this invention, there-

fore I reserve to myself the right to make such changes as fairly fall within the scope thereof.

Having thus described my invention, I claim as new and desire to secure by Letters Patent:—

A seal for a lock, comprising a fragile plate including two apertured extension members, said plate and members being 10 adapted to be applied on the casing of a lock having a key hole as well as a shackle, a fixed pin with a head protruding from the casing in spaced relation to the key hole for being engaged by one of the apertured members of the plate, and a pin rotatable in the 15 casing with the opening and closing move-

ments of the shackle, said pin protruding from the casing and having a head over which the second apertured member of the plate is guided so that with the closing 20 movement of the shackle on the casing the plate will be caused to be removably held on the casing by the pins whereby breakage of the plate will be required to obtain access to the key hole. 25

This specification signed and witnessed this 28th day of February, A. D. 1919.

IRA A. McCORMACK.
